UNITED STATES PATENT OFFICE

2,506,380

FOLDAWAY STAIRWAY

John P. Myers, Portsmouth, Va.

Application September 27, 1946, Serial No. 699,832

1 Claim. (Cl. 238—50)

1

This invention relates to improvements in fold-away stairways.

An object of the invention is to provide an improved foldaway stairway which will be concealed by a hinged trap door in a ceiling, and located in an opening in the floor joists of an upper floor, whereby the trap door may be swung downwardly and the foldaway stairway swung down into a straight line to extend to the floor level of the lower floor of a house to permit a person to ascend the stairway from the lower floor to the upper floor.

Another object of the invention is to provide an improved foldaway stairway comprising hinged sections pivotally supported in a well formed in the floor joists of an upper floor, the same being held in closed or folded position by means of a coil spring, and being suitably tied to a hinged trap door by a sliding tether, whereby when said trap door is opened, the stairway will be simultaneously opened.

A further object of the invention is to provide an improved collapsible and disappearing fold-away stairway which will be highly efficient in operation, and relatively inexpensive to manufacture and produce.

Other objects will appear as the description proceeds.

In the accompanying drawings which form a part of this application,

Figure 1 is a vertical sectional view through the foldaway stairway showing the same in retracted or concealed position;

Figure 2 is a detailed sectional view taken on the line 2—2 of Figure 1;

Figure 3 is a vertical sectional view through the foldaway stairway showing the same being partially open and with the trap door in opened or lowered position;

Figure 4 is an enlarged detail view of one of the stairway hinge members with spring supporting rope guide thereon;

Figure 5 is an enlarged detail view of a portion of the lower stairway section showing the guide rod for the trap door connecting tether rope, and

Figure 6 is a vertical sectional view through the foldaway stairway in open or lowered position.

Like characters of reference are used throughout the following specification and the accompanying drawings to designate corresponding parts.

In carrying out the invention, there is provided an improved foldaway stairway adapted to be positioned or housed in a substantially rectangular well 1 formed in the floor joists 2 of an up-

2

per floor, the same being closed by a trap door 3 hinged at 4 at one end of said well 1 to extend flush with the ceiling 5 of the lower floor.

A pair of bracket members 6 will be secured by the bolts 7 to one end wall of the well 1, and will pivotally support the cross shaft or axle 8 therebetween.

The upper section of the foldaway stairway is generally denoted by the reference numeral 9 and comprises the spaced parallel extending runners 10 and interconnected stair treads 11 secured therebetween and braced by the cross cleats 12.

Metal bracing strips 13 will be secured to the outer sides of the upper ends of said runners 10 and are apertured to receive and support the shaft or axle 8 which extends between said runners 10 and into the bracket members 6.

Posts 14 and 15 are respectively supported by the upper floor and on the lower end of the upper stairway section 9, and the upper ends thereof are connected by means of the chain 16 which serves as a hand rail when ascending or descending the stairway.

An arcuate channeled guide member 17 is secured to the axle 8 at the pivoted end of the stairway section 9, and supports an end of the rope 18 which is secured at its opposite end to one end of the heavy coil spring 19 fixed to the bracket 20 screwed to one side of the well 1, whereby the coil spring will be distended when the stairway is lowered, and will be contracted when the stairway is in its raised position.

The lower section of the foldaway stairway is generally designated by the reference numeral 21, and comprises the spaced parallel runners 22 and connecting stair treads 23 which are braced by the cleats 24.

An arcuate hand rail 25 is secured to one runner 22 on the same side of the stairway with the hand chain 16.

The adjacent ends of the stairway sections 9 and 21 are pivotally connected together by means of the heavy strap hinges 26 secured to the runners by means of the screws or bolts 27.

A longitudinally extending guide rod 28 is attached to one end of the runner 22 to extend in parallel spaced relation thereto, and supports a ring 29 to which the tether rope 30 is attached, the opposite end of said rope 30 being attached to a hook 31 in the upper surface of the hinged trap door 3.

A screw eye 32 will be secured in the lower surface of the trap door 3 at the end remote from its hinge 4 and will support a depending stair-

way opening rope 33 which will extend downwardly within reach of a person on the lower floor, whereby when it is desired to open and lower the foldaway stairway, it is only necessary to pull down on the rope 33, thereby lowering the trap door 3 and pulling the hinged sections of the stairway downwardly against the action of the coil spring 19 until the sections 9 and 21 are in alignment and extend to the floor level of the lower floor of the building, at which time 10 the stairway may be ascended. When it is desired to retract the stairway, it is only necessary to push upwardly on the same, and the distended coil spring will pull the folded or hinged sections of said stairway into their inoperative position and again close the trap door 3.

From the foregoing description, it will be apparent that there has been devised and provided a highly efficient foldaway stairway which may be manufactured and produced at a relatively low cost.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

A foldable stairway mountable in an opening in a ceiling which receives the stairway when folded comprising; an upper and lower pivoted

5 stair section, a trap door covering said opening, supporting brackets secured in said opening, a pivot member journalled in said brackets for pivotally supporting the upper section, a guide element on said pivot member and disposed in the opening, resilient means connected between said guide element and a wall of said opening for biasing the upper section into said opening, a post vertically mounted adjacent to the opening, a similar post carried by the upper section and a flexible member connected between the posts for limiting the downward movement of the upper section, a guide rod supported on the lower section, a ring slidably supported thereon, a tether rope secured to said ring and to the trap door for moving said lower section downward in response to the opening of the trap door, and means for aligning said upper and lower sections when in lowered operative placement.
